UNITED STATES PATENT OFFICE.

CHARLES F. PEARSON, OF FLUSHING, NEW YORK.

PLUG ATTACHMENT.

Application filed May 4, 1925. Serial No. 27,632.

This invention relates to electric plug devices and particularly to devices of this class for use in connection with electric sockets and principally wall sockets; and the object of the invention is to provide a plug of the class specified with means for facilitating the withdrawal or removal of a plug from a socket to prevent wear and tear on the electric cord in connection with which the plug is employed, and also to facilitate the easy withdrawal or removal of the plug; a further object being to provide an attachment which may be detachably mounted in connection with the plug and is provided with laterally directed hook-shaped arms adapted to receive two or more fingers of a hand in the use of the device, said attachment being apertured to permit the passage of the contact members or terminals of the plug therethrough and being composed of insulated material or being insulated from the terminals of the plug; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a side view of a plug showing one form of my attachment mounted thereon with part of the construction in section.

Fig. 2 is a face view of the construction shown in Fig. 1.

Fig. 3 is a view similar to Fig. 1 but showing a modification; and,

Fig. 4 is a face view of the construction shown in Fig. 3.

In Figs. 1 and 2 of the drawing, I have shown at 5 one form of attachment which I employ which comprises a dish-shaped or cup-shaped cylindrical body 6, the walls of which are extended at opposite points to form outwardly curved arms 7, the recesses 8 of which are adapted to receive the fingers of a hand and the transverse wall of the body 6 is provided with apertures 9 through which

the terminals 10 and 11 of an electric plug 12 are adapted to pass. The body of the plug 12 fits snugly within the cup-shaped body 6.

The attachment 5 shown in Figs. 1 and 2 of the drawing is preferably composed of insulating or non-conducting material in order that the terminals 10 and 11 may be insulated one from the other but instead of this construction I may employ an attachment 5 as seen in Figs. 3 and 4 of the drawing which is the same general form as the attachment 5 shown in Figs. 1 and 2 and comprises a cup-shaped body 14 having laterally directed and curved hook-shaped arms 15 provided with inwardly pressed parts 16 adapted to engage an enlarged annular portion 12^a on the plug 12. The attachment 13 is composed of sheet metal and is provided with two comparatively large apertures 17, and in practice a gasket 18 of insulating material is placed between the face of the plug 12 and the inner face of the attachment 13, said gasket having outwardly projecting bushings 19 and 20, which extend into the apertures 17 and serve to insulate the terminals 10 and 11 from the attachment 13.

With both forms of construction shown, it will be understood that the attachment is mounted in connection with the plug 12 prior to its placement in an electric socket, and when it is desired to remove the plug 12 from the socket, the fingers of a hand are placed in engagement with the arms 7—15 and the removal of the plug is facilitated by pulling outwardly on said arms. The inwardly projecting member 16 on the arms 15 of the attachment 13 serve to lock the plug 12 within said attachment to prevent the accidental displacement thereof. However the spring tension on the arms themselves may be sufficient to accomplish this result or to frictionally retain the plug 12 in position or in connection with the attachment. It will also be understood that I am not necessarily limited to the specific means or method of accomplishing the desired result herein set out and as the provision of laterally projecting elements of any kind or class on a plug for the purpose specified may be employed, and various other changes in

modifications of the construction herein shown and described may be made within the scope of the appended claims without departing from the spirit of my invention or sacrificing its advantages.

Having fully described my invention, what I claim as new and desire to secure by Letters Patent, is:—

1. An attachment for electric plugs of conventional form adapted for attachment with the plug without altering the structure thereof, said attachment comprising a cup-shaped body adapted to be mounted on said plug and provided with laterally and radially projecting arm members adapted to receive the fingers of a hand in the removal of a plug from an electric socket.

2. An attachment for electric plugs of conventional form adapted for attachment with the plug without altering the structure thereof, said attachment comprising a cup-shaped body adapted to be mounted on said plug and provided with laterally and radially projecting arm members adapted to receive the fingers of a hand in the removal of a plug from an electric socket, and means for insulating the attachment from the terminals of the plug.

3. An attachment for electric plugs of conventional form adapted for attachment with the plug without altering the structure thereof, said attachment comprising a cup-shaped body adapted to be mounted on said plug and provided with laterally and radially projecting arm members adapted to receive the fingers of a hand in the removal of a plug from an electric socket, and means for retaining the attachment against accidental displacement from the plug.

4. An attachment for electric plugs of conventional form adapted for attachment with the plug without altering the structure thereof, said attachment comprising a cup-shaped body adapted to be mounted on said plug and provided with laterally and radially projecting arm members adapted to receive the fingers of a hand in the removal of a plug from an electric socket, means for retaining the attachment against accidental displacement from the plug, and means for

insulating the attachment from the terminals of the plug.

5. An attachment for electric plugs of conventional form adapted for attachment with the plug without altering the structure thereof, said attachment comprising a cup-shaped body, the bottom of which is provided with apertures through which the terminals of the plug are adapted to pass in mounting the attachment on the plug, the side walls of said attachment encircling the side walls of the plug, and the side walls of said attachment having at their outer ends, outwardly and radially projecting finger pieces.

6. An attachment for electric plugs of conventional form adapted for attachment with the plug without altering the structure thereof, said attachment comprising a cup-shaped body, the bottom of which is provided with apertures through which the terminals of the plug are adapted to pass in mounting the attachment on the plug, the side walls of said attachment encircling the side walls of the plug, and the side walls of said attachment having at their outer ends, outwardly and radially projecting finger pieces, and means for insulating said attachment from the terminals of said plug.

7. An attachment for electric plugs of conventional form adapted for attachment with the plug without altering the structure thereof, said attachment comprising a cup-shaped body, the bottom of which is provided with apertures through which the terminals of the plug are adapted to pass in mounting the attachment on the plug, the side walls of said attachment encircling the side walls of the plug, and the side walls of said attachment having at their outer ends, outwardly and radially projecting finger pieces, means for insulating said attachment from the terminals of said plug, and means for tensionally retaining the attachment against accidental displacement from the plug.

In testimony that I claim the foregoing as my invention I have signed my name this 28th day of April 1925.

CHARLES F. PEARSON.
